TOY FERRY SYSTEM

William L. Shepheard, Norfolk, Va.

Application March 26, 1946, Serial No. 657,134

3 Claims. (Cl. 46—96)

1

This invention relates to toys and, more particularly, a toy ferry boat system including a wheeled miniature ferry boat, a pair of docks, and mechanism for shuttling the ferry boat between the docks.

The primary object of the invention is to provide a wheeled ferry boat capable of operation on a floor or other generally flat surface, a pair of docks functioning as termini, and a pulley system connecting the docks and boat so that both may be driven back and forth between the docks by one or more children as a single or joint venture. Additionally the ferry boat is intended to be provided with miniature vehicle carrying facilities. The docks are to be provided with ramps extending from floor level upwardly to the dock surface, and the boat and docks are to have complementary ends so that the vehicles may be passed directly from the docks to the boat and vice versa.

Another object is to provide, on each of the docks, a mechanism including a pulley, an easily accessible crank for rotating the spool, and a string windable on the spool and having one end attached to the ferry boat so that the boat may be pulled to either dock by turning the crank. It is another object to provide, on each of the docks, a housing simulating a toll house, the spool for each dock being mounted for rotation about a vertical axis within each house, and a crank shaft extending from the spool upwardly through the top of the house with the crank disposed exteriorly on the upper end of the shaft. Still again it is intended to provide guides for the string so that the string will run from the spool downwardly through the bottom of the dock and thence to the boat.

It is likewise intended to provide the boat and docks with miniature elements simulating those which characterize an actual ferry boat system. Additionally, it is proposed to form the ends of the docks and the ends of the ferry boat complementary with one another to facilitate packing in such manner that the entire system can be visualized in operation while the elements are packed.

These and other objects will be apparent from the following specification and drawings in which:

Fig. 1 is a plan view of the assembly; and,

Fig. 2 is a side elevation, partially in vertical section along the line 2—2 of Fig. 1.

Referring to the drawings in which like reference numerals denote similar elements, the ferry boat indicated at 2 is preferably formed of

2

sheet metal, and includes a main or vehicular deck 4, beneath which on suitable bearings 5 are rotatably mounted wheels 6 so that the boat may be rolled fore and aft. The boat is preferably provided with elements simulating those which characterize a large ferry boat, including a superstructure 8, windows 9, smoke stack 10, and pilot house 12 at each end of the superstructure. Guard chains 14 are preferably detachably connected as indicated at 15 across each end of the main deck so as to prevent dislodgement of miniature vehicles off the convexly curved ends of the boat.

Miniature docks 18 are provided, each dock 15 being supported on piles 22 so that the dock surfaces, which are preferably formed of wood, are substantially at the level of main deck 4. Each dock is provided with suitable guard rails 24, a toll house 26, and a flat ramp 28 extending 20 downwardly from the dock to the floor, each ramp being detachable by lifting the end, which is held on suitable rests on the edge of the dock.

The driving mechanism comprises a crank 30 having its shaft 32 rotatably fitting through openings 34 and 35 respectively in the top of each toll 25 house 26 and dock 18, each shaft 32 having rigidly fixed thereon a spool 36 which constitutes a reel for string. A guide 38 is provided between the spool and an inclined channel 40 extends 30 through dock 18 to provide free running of a string 42 which has one end attached to spool 36 and the other end attached as indicated in 44 to the under side of ferry boat 2.

It will be apparent that when the system is 35 set up with docks 18 spaced from one another and with ferry boat 2 therebetween, the boat may be pulled towards either dock by rotation of the appropriate crank 30. If the boat is pulled towards one dock, string 42 is unreeled from the 40 spool on the other dock, this latter spool being then left to run free. When the system is packed or otherwise stored, the docks are nested respectively with the ends of the ferry boat, and preferably the string is wound on both spools.

45 The invention detailed above is not limited to the specific disclosure but is intended to cover modifications and substitutions within the scope of the following claims.

I claim:

50 1. A toy ferry boat and dock system, comprising a wheeled toy boat simulating a ferry boat and having an end simulating a vehicle loading arrangement, a toy dock having an end simulating a vehicle loading arrangement for cooperation 55 with the end of the ferry boat, a housing on

the dock simulating a toll house, a shaft in said housing mounted for rotation about a vertical axis and having a portion extending exteriorly through the roof of said housing, a reel in said housing carried by said shaft, string guide means extending through said dock to the under side thereof, and a string or the like pulling element attached to said ferry boat and running to the under side of said dock, through said guide means and to said reel, whereby to pull said ferry boat to said dock upon rotation of said crank.

2. A toy ferry boat and dock system, comprising a toy boat simulating a ferry boat, said boat having wheels thereon for running on a surface and a deck terminating in similar convexly rounded ends simulating vehicle loading arrangements, and a pair of toy docks, each comprising posts simulating piling and platforms supported by the piling at the level of said deck, said docks having ramps adapted to be inclined upwardly from the level of said surface to said platform on one side thereof and being concavely rounded on the other side so as to be substantially complementary with the ends of said boat, whereby said docks and said boat may be nested in end-to-end series.

10

20
25

3. In the combination claimed in claim 2, reels on said docks, manually rotatable means for rotating said reels, and strings or the like pulling elements on said reels, said strings being attached to said ferry boat whereby the latter may be shuttled between said docks by rotation of the appropriate reel.

WILLIAM L. SHEPHEARD.
